[57] CLAIM

The ornamental design for a toilet roll dispenser, as shown and described.

DESCRIPTION

FIG. 1 is a top, front, and left-side perspective view of a toilet roll dispenser showing my new design, the broken-line disclosure of several toilet rolls being for illustrative purposes only and forming no part of the claimed design;

FIG. 2 is a left side elevation view thereof;

FIG. 3 is a front elevation view thereof;

FIG. 4 is a right side elevation view thereof;

FIG. 5 is a rear elevation view thereof;

FIG. 6 is a top plan view thereof; and,

FIG. 7 is a bottom plan view of the design.

FIG.1.

FIG. 2.

FIG. 3.

FIG.4.

FIG.5.

FIG. 6.

FIG. 7.
